UNITED STATES PATENT OFFICE.

GARRIE H. RHEUTAN, OF HARTFORD, CONNECTICUT.

STEAM-BOILER.

SPECIFICATION forming part of Letters Patent No. 269,114, dated December 12, 1882.

Application filed June 6, 1882. (Model.)

To all whom it may concern:

Be it known that I, GARRIE HERRING RHEUTAN, of the city and county of Hartford, of the State of Connecticut, have invented a new and useful Improvement in Steam-Boilers; and I do hereby declare the same to be described in the following specification and represented in the accompanying drawings, of which—

Figure 1 is a front end view, and Fig. 2 a vertical and longitudinal section, of a boiler provided with my invention, the nature of which is defined in the claims hereinafter presented. Fig. 3 is a horizontal section taken through the water-leg and front plate of the boiler.

My invention relates to the boiler-shell and water-leg and to the "front plate" applied thereto.

In the drawings, A represents the cylindrical shell or body of the boiler, having extended through it from end to end a stack of flue-tubes, a, there being at the front end of the boiler-shell a smoke box or chamber, B. Extending from and below the shell of the boiler is the water-leg C, which constitutes the front of the fire-place, and has its front flush or in one vertical plane with the front end or head of the cylindrical body or shell of the boiler. A flange, D, in prolongation of the upper half of the shell, projects from the front end of the boiler, and also from the vertical ends l l of the water-leg, to the front plate, E, which is provided with two horizontal flanges, b c, arranged to extend from it rearward to the water-leg. The said plate, with its flanges b and c, forms, with the flush fronts of the boiler-head and water-leg, the smoke box or chamber B and a throat, F, opening out of which into the

fire-place and extending through the water-leg is the tubular mouth G of the fire-place. 40 The said mouth G is provided with a door, d, and there is also in the front plate an opening, e, into the smoke-box, which opening is directly in front of the stack of flue-tubes, and is furnished with a door, f, to open upward. The 45 ash-pit door g is in the lower portion of the front plate. The smoke-box, at its top, is provided with an educt, h, for the discharge of the smoke from it.

In the operation of the boiler, the smoke and volatile products of combustion escaping from the fire-place pass through a flue, i, beneath the boiler to a flue, k, in rear of it, thence through the stack of tubes and into and through the smoke-box.

What I claim as my invention is as follows— that is to say:

1. The tubular boiler having the front of its water-leg flush with the front head of the boiler-shell, and with such head provided with the 60 arched flanges to project from the shell and the opposite ends of the said water-leg, as set forth.
2. The combination of the front plate, E, provided with the two flanges b c, extending from it, 65 as set forth, with the tubular boiler having the front end of its shell even or flush with the front of the water-leg of such boiler, and also having the arched flange to project from such end and from the opposite vertical ends of the 70 water-leg to the said flush plate, all being substantially as shown and specified.

GARRIE HERRING RHEUTAN.
